(57) **CLAIM**

The ornamental design for a digital audio player with mixer, as shown and described.

DESCRIPTION

FIG. 1 is a top plan view of a digital audio player with mixer showing the new design;

FIG. 2 is a bottom plan view of the digital audio player with mixer;

FIG. 3 is a front elevational view of the digital audio player with mixer;

FIG. 4 is a back elevational view of the digital audio player with mixer;

FIG. 5 is a right side elevational view of the digital audio player with mixer; and,

FIG. 6 is a left side elevational view of the digital audio player with mixer.

The subject matter shown in broken lines in FIGS. 1 and 2 is disclaimed and forms no part of the claimed design.
